UNITED STATES PATENT OFFICE.

MORRIS WEINER AND ISIDOR J. RIFKIN, OF NEW YORK, N. Y.

DESIGN FOR A FINGER-RING OR SIMILAR ARTICLE.

51,448.

Specification for Design.

Patented Oct. 30, 1917.

Application filed May 8, 1917. Serial No. 167,361. Term of patent 7 years.

To all whom it may concern:

Be it known that we, MORRIS WEINER and ISIDOR J. RIFKIN, citizens of Russia, and residents of the city and State of New York, have invented a new, original, and ornamental Design for a Finger-Ring or Similar Article, of which the following is a specification, reference being had to the accompanying drawing, forming part thereof.

Figure 1 of the drawing is a perspective view of our new design.

Fig. 2 is a front elevation of the design.

What we claim is:

The ornamental design for a finger ring or similar article, as shown.

MORRIS WEINER.
ISIDOR J. RIFKIN.
